UNITED STATES PATENT OFFICE.

ALEXANDER B. RONEY, OF CHICAGO, ILLINOIS.

LEVER-CONTROLLED PADDLE-ACTION FLYING MACHINE.

Application filed December 8, 1921. Serial No. 521,013.

To all whom it may concern:

Be it known that I, ALEXANDER B. RONEY, a citizen of the United States of America, residing at Chicago, in the county of Cook 5 and State of Illinois, have invented a new and useful Lever-Controlled Paddle-Action Flying Machine, of which the following is a specification.

I show herewith a feathering paddle 10 wheel propeller as combined in pairs to a fuselage with which the multiple members are made to co-act and propel said fuselage upward, downward, forward, backward and sideways, as follows:

15 Fig. 1, is a partial cross section of Fig. 2, on line *c-c*.

Fig. 2, is a partial cross section of Fig. 1, on line *b-b*.

20 Fig. 3, is a view in elevation of Fig. 4.

Fig. 4, is a transverse plan view of Fig. 3.

Fig. 2, shows that the paddle parts 15, 15, are accessible and that said paddle parts are separately mounted in the frame 1, on 25 their own axle members 2, 2, which are pivotally aligned in the plane of frame 1, and shouldered in their respective bearings F, F, against end thrust, and that the opposite ends of said axle parts each carry a 2

30 to 1 reduction gear part 3, in mesh with the stationary gear 4, around which they are carried by frame 1, in its orbit around the axis of the driving shaft 5, to effect a continuous rotation of the paddle members on 35 their own axle parts 2, 2, in opposite directions.

Fig. 1, shows that the gear part 4, is carried on the outer end of the sleeve part 6, which is journaled adjustably in the fuselage 7, and that said sleeve 6, can, by means 40 of lever 9, be rotated in its fuselage bearing and locked to the fuselage proper by the trigger piece 40, carried on lever 9, when it is engaged to any one of the spaced 45 notches cut in the periphery of the ring part 50, that surrounds said sleeve part 6; said ring part 50, is held rigid to the fuselage by a projecting bracket which lies beneath sleeve 6, and is indicated by dotted 50 lines.

Fig. 1, also shows that drive-shaft 5, is connected to the outer portion of the lubricant casing 12, which includes the journal caps 13, 13, by means of which the said 55 drive shaft is bolted to the outer side of frame 1, thus making them both a one-piece

assembly in which the aligned and quartered paddle parts 15, 15, are mounted and strongly supported for continuous rotation of the paddle members, from flat to edge and 60 edge to flat by their gear parts 3, 3, now in running mesh with the stationary gear part 4, and which is adapted to be turned on its own axis around the driving shaft 5, by the distant control lever 9, that is located in 65 the fuselage nacelle for shifting the radial point at which the paddles strike flat against the air for purposes of directional propulsion referred to elsewhere.

2 to 1, gear reduction here means that 70 only one side of each rotating paddle strikes flat in its circuit around the axis of the driving shaft 5; in other words, said paddles make only one $\frac{1}{2}$ turn on their own axles 75 to their one rotation around the axis of shaft 5, on which they are rotatably mounted.

I now adapt this said $\frac{1}{2}$ turn quartered paddle wheel propeller unit to a fuselage and propel it through the air driven by a 80 motor means under lever control as follows:

Figs. 3 and 4 represent my flying machine equipped with my $\frac{1}{2}$ turn propeller units in pairs.

In Fig. 4, the numeral 7 indicates the 85 standard type of fuselage, but in this instance, the body part is split along the center line *a-a*, after the manner of a journal bearing to enclose the motor parts and support the outer ends of the lateral driving 90 axles 5, 5 in the sleeve parts 6, 6, 6, 6, which are adjustably journaled between both halves of the fuselage proper. The said sleeves and said axle parts project from the sides of the fuselage proper and mount my 95 $\frac{1}{2}$ turn propeller units on their outer ends. Midway of their length the lateral driving axles 5, 5 carry roller gear parts 8, 8 by means of which they are connected together through the motor drive shaft 14, to stand 100 at equal distance on opposite sides of the fuselage center of gravity.

Then by means of right and left hand levers 9, 9 and the endless chain belt parts 17, 17 that are wrapped around the hub portions of the quartering sleeves 6, 6 and 6, 6, the said sleeves are thereby made to reverse in their fuselage bearings back and forth by a push and pull of said levers which are fastened to said sleeves.

110 In operation, the motor revolves the fore and aft propeller units in reverse directions

as is indicated by arrows in Fig. 3, that is, they are revolved inversely to the center of fuselage gravity to lift up the machine, which means that the leverage of the paddle units is inversely balanced over the fuselage center of gravity.

Now the operator moves both levers as one to turn and radially position alike all the journaled sleeve parts 6, on both sides of the fuselage and thereby set all the paddles to the horizontal position so as to make the flat side of each paddle part strike downward on the air simultaneously and elevate the machine, then the operator moves both levers as one for forward travel. This means that the aft-paddles have been shifted by the sleeve parts 6, so that their flat sides strike flat against the air above the axis line $a-a$, and the fore paddles have been shifted to strike flat beneath the axis line $a-a$. Then the operator moves the right hand lever to shift the right hand sleeves, and steer the machine to the right, then puts it back to zero; then moves the left hand lever to shift the sleeves on that side of the fuselage to steer to the left, then to avoid gliding past a stopping point, he moves both levers as one to slow down. This means that the paddles aft have been shifted to strike flat beneath the axis line $a-a$, and the front paddles above said line $a-a$.

Now, to land the machine, the operator will move both levers as one and shift all the sleeve parts 6, to position all the paddles horizontally as shown to simultaneously strike flat downward on the air, which means that all the paddles have been set in the same position to land the machine as they were set to elevate it, but now the operator lets go of both levers, he leaves them placed, then throttles the speed of the

motor either fast or slow to raise or lower the machine.

Finally, the feathering paddle wheel units, by reason of their paddle parts turning from flat to edge while they are being carried around by the motor drives are only effective for purposes of propulsion through one $\frac{1}{3}$ of their circuit through the air, but the other $\frac{2}{3}$ is not wasted for it is employed sidewise to automatically stabilize the flight of the machine. The plane and rudder parts A and B are both shown in Figures 3 and 4.

I claim:

1. A feathering paddle wheel propeller comprising a frame mounted on a right angle drive shaft rotatably supported in an adjustable sleeve bearing aligned axles on said frame and carrying quartered paddles, gears mounted on said axles and on said sleeve bearing, said gears having a two-to-one ratio respectively, and a lubricant casting integral with said frame and enclosing said gears.

2. In a flying machine, a fuselage, fore and aft transverse shafts means for rotating said shafts reversely, pairs of half-turn paddle wheel propellers mounted on said shafts and projecting latterly from the sides of said fuselage, means for half-turning the paddles of said propellers at each revolution, means for enclosing said turning means, pairs of adjustable bearings for said transverse shafts on said fuselage, a drive common to a pair of bearings on either side of said fuselage and a lever control for one bearing of each pair.

ALEXANDER B. RONEY.
